Primary Examiner — Mojtaba Tehrani(74) *Attorney, Agent, or Firm* — Schwartz Law Firm, P.C.(57) **CLAIM**

The ornamental design for a rifle barrel as shown and described.

DESCRIPTION

FIGS. 1 and 2 are front perspective views of the rifle barrel; FIGS. 3 and 4 are rear perspective views thereof;

FIG. 5 is a side view thereof;

FIG. 6 is a rear end view thereof; and,

FIG. 7 is a front end view thereof.

The portions of the rifle barrel shown in broken-lines form no part of the claimed design.

1 Claim, 5 Drawing Sheets(56)
